(57) **CLAIM**

The ornamental design for a stacking water filter dispenser, as shown and described.

DESCRIPTION

This application is related to copending application Serial No. 13/594,084, filed Aug. 24, 2012.

FIG. 1 is a top, side and front perspective view of the first embodiment of a stacking water filter dispenser showing our new design;

FIG. 2 is a top plan view thereof;

FIG. 3 is a bottom plan view thereof;

FIG. 4 is a right side elevation view, the left side elevation

being a mirror image thereof;

FIG. 5 is front elevation view thereof;

FIG. 6 is a rear elevation view thereof;

FIG. 7 is a cross-sectional view taken along line 7-7 of FIG. 2;

FIG. 8 is a cross-sectional view taken along line 8-8 of FIG. 2;

and,

FIG. 9 is a bottom, side and front exploded view of the

stacking water filter dispenser shown in FIG. 1.

The broken lines showing a spigot and canister body are for illustrative purposes only and forms no part of the claimed design.
